UNITED STATES PATENT OFFICE.

CHARLES BEMIS REARICK, OF NEW LONDON, CONNECTICUT, ASSIGNOR TO CONNECTICUT TURBINE MANUFACTURING COMPANY, OF NEW LONDON, CONNECTICUT, A CORPORATION OF CONNECTICUT.

AXIAL-FLOW STEAM-TURBINE.

1,077,300.

Specification of Letters Patent.

Patented Nov. 4, 1913.

Application filed December 9, 1912. Serial No. 735,602.

To all whom it may concern:

Be it known that I, CHARLES BEMIS REARICK, a citizen of the United States, and resident of New London, county of New London, State of Connecticut, have made a certain new and useful Invention Relating to Axial-Flow Steam-Turbines, of which the following is a specification, taken in connection with the accompanying drawings.

10 This invention relates to axial flow turbines for use with steam or other elastic motive fluid, the turbine wheels being preferably cast with a number of annular series of inclined stepped curved buckets with which

15 coöperate suitable nozzle and return members provided with curved return passages preferably arranged at different angles to assist in securing the desired increase of area of the bucket and return passages as the steam

20 passes the desired number of times through the various wheel buckets. The turbine wheel may also be formed with especially arranged expansion spokes of material having generally similar expansion to the wheel

25 rim which may have their inner ends secured to the hub while the body of the spokes is loosely embraced in any desired way by spoke supports which may be cast integral with the wheel hub, if desired.

30 In the accompanying drawing showing in a somewhat diagrammatic manner an illustrative embodiment of the invention, Figure 1 is a partial axial section taken along the line 1—1 of Fig. 2 in which the wheel buckets and return passages have been turned up into the line of section to more clearly show their construction. Fig. 2 is a transverse sectional view taken along the line 2—2, 2^a—2^a and the other section lines

35 shown in Fig. 1 to the extent indicated on Fig. 2 so as to show therein more clearly the arrangement of the various sets of wheel buckets and return passages. Fig. 3 is a developed flow diagram in which the return members and passages are shown in dotted

40 section.

In the illustrative embodiment of this invention shown in the drawings, the turbine wheel may be formed in any desired way

45 with the selected number of annular series of wheel buckets having the desired form and the wheel rim and buckets may be conveniently cast in one piece of specially strong bronze or other suitable material as

by the process covered by the Hopson and 55 Rearick Patent No. 1,008,478, of November 14, 1911.

Suitable spokes preferably of bronze or other material having substantially the same or slightly greater co-efficient of expansion 60 than the rim material are preferably formed integral with or otherwise secured to the rim which may be conveniently done by casting the rim around the same, the spokes 65 having as indicated in Figs. 1 and 2 suitably formed projections, such as the annular ribs 37 which are strongly gripped by the inclosing portions of the rim material which may have suitable inwardly projecting lugs 47 extending from the rim 5. The 70 inner ends of these spokes which are preferably formed with gripping projections such as the annular projections 36 may be conveniently secured to the wheel as by casting the steel, cast iron or other suitable 75 metal used for the hub 48 around them so as to firmly grip the inner ends of the spokes thus effecting relief of original casting strains in rim and spokes; if desired the hub metal may extend out along the spokes 80 so as to form spoke supports laterally supporting the spokes throughout the desired extent while preferably allowing the longitudinal expansion of the spokes beyond the point at which their inner ends are secured 85 to the hub. For some reasons it is desirable in order to insure the accurate alinement of these spokes during such expansion as takes place under operating conditions to interpose a spoke sleeve 25 of steel or other suitable material around each of the spokes 26 before casting the hub metal 48 around the spokes so as to rigidly secure their inner 90 ends in position, this metal preferably extending around the spoke sleeve throughout substantially the entire length of the spoke so as to form a rigid spoke support 95 to add to the rigidity of the wheel construction. In this way when the wheel becomes heated under normal operating conditions the bronze rim expands considerably 100 and the similar or still more expansible spokes expand and move longitudinally within their supports and sleeves so as to minimize heat and expansion strains in the 105 wheel.

The wheel may be conveniently mounted on a suitable shaft 35 which may be mounted

in the turbine casing 1 of any desired form or construction, the wheel preferably having its spokes inclosed as by suitable side plates 40 which may be mounted in lateral recesses in the wheel rim and firmly secured in position as by the bolts 41.

The casing 1 may be formed with a suitable admission passage 2 which may be cast integral with the casing if desired and within this casing there may be mounted in any desired way a series of nozzle members and return passages each of which may if desired be in the form of an integral casting 22 having a nozzle tube 3 held in the casing 15 in any desired way so as to support the nozzle and return member in position in proper coöperation with the wheel. If desired suitable alining pins 42 may be formed in the nozzle and return members so as to coöperate with suitable alining sockets, such as 43, in the adjacent members and assist in holding the members in proper circumferential alinement. As shown in Figs. 1 and 3 each of these nozzle and return members 20 may be provided with a series of injecting nozzles 4 arranged to coöperate with the first set of buckets 6 in the wheel. These return members 22 may be formed as by casting them integral therein with a number of series of return passages adapted to return the steam received from each set of wheel buckets into the succeeding set so that the steam is passed the desired number of times through the wheel buckets to 25 exert additional propelling impulses thereon. As shown in Fig. 2 by the line of arrows the steam naturally advances somewhat in the direction of motion of the turbine wheel during its passage axially across the 30 same through the different series of buckets. For this reason the different return passages in this return member may be arranged in a generally diagonal direction, it being, however, desirable to arrange special 35 trailing and advance return passages to receive the steam in the first set of return passages, for instance, when the injecting nozzles are in line with one of the partitions between the wheel buckets. For this 40 purpose the special or trailing return passage 27 may be provided in each return member 22 to receive this backwardly diverted or backsplit steam and a similar advance return passage 28 may be provided at 45 the other end of this first series of return passages 10. For similar reasons the trailing return passage 30 and the advance return passage 29 may be provided at either end of the similarly shaped return passages 50 55 60 65

cases the regular return passages are 20 and the trailing return passage 33 and the advance return passage 34. In order to prevent clogging of steam, it is desirable to form the return members 22 so that they are somewhat separated from the adjacent return members as by the relief spaces 44, 45 and 46. It is desirable to form the annular partitions between the different sets of return passages and wheel buckets with curved annular recesses such as 49, 50 which serve to receive any surplus steam beyond what can conveniently enter the succeeding return passage or wheel bucket and curve it around so as to again direct it against the inner side into this stream of motive fluid. 70 75 80

The steam originally injected into the first set of wheel buckets from the injecting nozzles 4 has a high velocity and correspondingly high kinetic energy. At each pass through the wheel buckets the velocity and kinetic energy are reduced so that the stream of motive fluid thus has an increased volume at each pass which should be accommodated by increasing the available cross-section of the succeeding wheel buckets and return passages. This can be effectively done by increasing the angle at which the steam is injected into the succeeding sets of buckets and also by increasing the axial width across the curved row of wheel buckets or return passages so as to allow a greater width to the curved stream of steam passing therethrough or if desired the succeeding set of wheel buckets for instance may both 90 95 have an increased angle and a greater width so as to secure through both these factors the desired increase in available cross-section and accommodate the increased volume of steam. As shown in Fig. 2 the injecting 100 nozzles 4 are arranged at a slight angle to the wheel circumference at this point so that the steam is directed properly into the first set of curved wheel buckets 6 which are arranged at a relatively slight angle to 105 take full advantage of the high velocity of the injected steam, thus making the perpendicular distance between the partitions of this set of buckets, that is, their bucket height correspondingly small. The steam 110 passing through this first set of buckets 6 is under normal operating conditions discharged therefrom at a correspondingly greater angle due to its reduced velocity and the wheel motion and the first set of return 115 passages 10 into which the steam passes have their receiving throats or sides 7 arranged as shown in Fig. 1 at a greater angle substantially equal to the angle at which the steam is discharged from the first wheel 120 buckets, as shown in dotted lines in Fig. 2. The steam is with a minimum of disturbance or eddying received and guided around these return passages in substantially the same inclined plane until it is discharged 125 130

from the returning or injecting sides 8 of these buckets into the second set of wheel buckets 9. This second set of wheel buckets 9 are shown in full lines in that part of Fig. 2 in which the section is taken along the lines 2^a of Fig. 1 and as indicated the increased angle which these wheel buckets 9 make with the wheel circumference at that point correspondingly increases the perpendicular distance between the partitions of this set of wheel buckets so as to secure an increased height of buckets and corresponding increase in their effective area or capacity. The steam from the returning sides 8 of the return passages 10 entering these wheel buckets 9 leaves them at a still greater angle and to receive this steam under most advantageous conditions the second set of return passages 12 have their receiving ends 11 arranged at substantially the angle of the steam entering from the wheel buckets 9 as shown by the dotted lines in this part of Fig. 2. This set of intermediate return passages 12 is preferably warped so as to guide the steam received into their receiving ends 11 at a considerable angle so that when again delivered into the succeeding set of wheel buckets 14 from the returning sides 13 of these return passages 12 the steam makes a considerably less angle to the wheel circumference. This is shown quite clearly in the sectional view through these return passages taken along the line 2^b of Fig. 1 which is shown in that part of Fig. 35 which is correspondingly designated. The receiving ends 11 of these warped return passages are therein indicated in dot and dash lines as being in front of the line of section, and the steam is shown as being guided by these warped buckets so as to be discharged from their returning sides 13 at a considerably sharper angle so as to properly coöperate with the sharp angle wheel buckets 14. These wheel buckets as indicated in Fig. 1 are given a considerably greater axial width in order to properly accommodate in their comparatively slight height the increased volume of steam during this pass through the wheel. The increase in axial width of the wheel buckets 9 as compared with the first set of wheel buckets 6 contributes to their increased carrying capacity as does also their increased angle as compared with the first set of wheel buckets 6.

As shown in Fig. 2 the steam discharged from the wheel buckets 14 passes into the dotted receiving ends 15 of the return passages 17 which are shown in full lines in the succeeding section on 2^c so that the steam may be definitely guided around in the same plane in these flat buckets 17 so that when discharged from their returning sides 16 it has a considerably greater angle and properly enters the fourth set of wheel

buckets 18 which have a correspondingly greater height because of their greater angle for which reason their axial width need not be any greater and may in some cases be even less than the axial width of the wheel buckets 14. The steam discharged from these wheel buckets 18 is directed in line with the dotted receiving sides 19 of the last set of return passages 20, so that when discharged from their returning sides 21 shown in full lines in the section on 2^d at the bottom of Fig. 2 the steam is directed at a very much greater angle to this part of the wheel circumference, so that the wheel buckets have a much greater height and effective area and can properly accommodate the increased volume of this slower moving steam which is indicated as being discharged directly into the wheel chamber from this last set of buckets.

By arranging the receiving sides of one or more of the sets of return passages at about the angle at which the steam is discharged from the preceding set of wheel buckets the steam is returned to the succeeding set of wheel buckets when each of the return passages is substantially flat at a sufficiently greater angle to materially increase the effective area of the wheel buckets when formed with substantially the same axial width and thickness of partition. In this way it is possible to largely or wholly eliminate the use of warped wheel buckets or return passages which are less desirable from the constructional standpoint because of the increased difficulty of properly forming or finishing them and which are somewhat undesirable because of the increased frictional losses involved. In order to most readily finish wheel buckets or return passages of this character they are preferably formed with somewhat elliptical or flattened curved bottoms so as to allow the use of a buffing or finishing tool to best advantage. In Fig. 1 the flattened curved bottoms of these buckets are designated 51, the buckets being sufficiently shallow to considerably facilitate finishing in this way.

Having described this invention in connection with a number of illustrative embodiments, forms, proportions, numbers of parts, arrangements, materials and processes of manufacture, to the details of which disclosure the invention is not of course to be limited, what is claimed as new and what is desired to be secured by Letters Patent is set forth in the appended claims.

1. In axial flow elastic fluid turbines, a cast turbine wheel rim provided with a number of annular sets of lapping curved buckets, substantially radial bronze expansion spokes secured to said rim, a wheel hub being formed of cast ferrous metal of less coefficient of expansion embracing and gripping said spokes adjacent their inner ends

and forming integral spoke supports loosely surrounding said spokes and allowing their radial expansion and said plates secured to said rim to inclose said spokes, said wheel buckets being substantially flat and a number of the succeeding sets of said wheel buckets being arranged at a greater angle to the wheel circumference than the preceding set, a series of return members mounted to coöperate with said wheel, each of said members being provided with a number of sets of curved return passages coöperating with the sets of wheel buckets, one or more sets of return passages being substantially flat and arranged at a greater angle than the wheel buckets from which they receive fluid.

2. In axial flow elastic fluid turbines, a cast turbine wheel rim provided with a number of annular sets of lapping curved buckets, bronze expansion spokes secured to said rim, a wheel hub being formed of cast ferrous metal of less co-efficient of expansion embracing and gripping said spokes adjacent their inner ends, said wheel buckets being substantially flat and a number of the succeeding set of said wheel buckets being arranged at a greater angle to the wheel circumference than the preceding set, a series of return members mounted to coöperate with said wheel, each of said members being provided with a number of sets of curved return passages coöperating with the sets of wheel buckets, one or more sets of return passages being substantially flat and arranged at a greater angle than the wheel buckets from which they receive fluid.

3. In axial flow elastic fluid turbines, a cast turbine wheel rim provided with a number of annular sets of lapping curved buckets, bronze expansion spokes secured to said rim, a wheel hub being formed of metal of less co-efficient of expansion embracing and gripping said spokes adjacent their inner ends, said wheel buckets being substantially flat and a succeeding set of said wheel buckets being arranged at a greater angle to the wheel circumference than the preceding set, a series of return members mounted to coöperate with said wheel, each of said members being provided with a number of sets of curved return passages coöperating with the sets of wheel buckets.

4. In axial flow elastic fluid turbines, a cast bronze turbine wheel provided with a number of annular sets of lapping curved buckets, said wheel buckets being substantially flat and a number of the succeeding sets of said wheel buckets being arranged at a greater angle to the wheel circumference than the preceding set and a number of the succeeding sets of said wheel buckets having a greater axial width than the preceding set, a series of nozzle and return members mounted to coöperate with said wheel, each of said members being provided with

a plurality of injecting nozzles to coöperate with the first set of wheel buckets and with a number of sets of curved return passages coöperating with the succeeding sets of wheel buckets, one or more sets of return passages being substantially flat and arranged at a greater angle than the wheel buckets from which they receive fluid and one of said sets of return passages being warped and arranged to return the fluid to the wheel buckets at a less angle to the wheel circumference than said fluid was received.

5. In axial flow elastic fluid turbines, a cast turbine wheel provided with a number of annular sets of lapping curved buckets, said wheel buckets being substantially flat and a number of the succeeding sets of said wheel buckets being arranged at a greater angle to the wheel circumference than the preceding set and a succeeding set of said wheel buckets having a greater axial width than the preceding set, a series of nozzle and return members mounted to coöperate with said wheel, each of said members being provided with a plurality of injecting nozzles to coöperate with the first set of wheel buckets and with a number of sets of curved return passages coöperating with the succeeding sets of wheel buckets, one or more sets of return passages being substantially flat and arranged at a greater angle than the wheel buckets from which they receive fluid.

6. In axial flow elastic fluid turbines, a cast turbine wheel provided with a number of annular sets of lapping curved buckets, said wheel buckets being substantially flat and a succeeding set of said wheel buckets being arranged at a greater angle to the wheel circumference than the preceding set and a succeeding set of said wheel buckets having a greater axial width than the preceding set, a series of nozzle and return members mounted to coöperate with said wheel, each of said members being provided with an injecting nozzle to coöperate with the first set of wheel buckets and with a number of sets of curved return passages coöperating with the succeeding sets of wheel buckets, one or more sets of return passages being substantially flat and arranged at a greater angle than the wheel buckets from which they receive fluid.

7. In axial flow elastic fluid turbines, a turbine wheel provided with a number of annular sets of lapping curved buckets, said wheel buckets being substantially flat and a succeeding set of said wheel buckets being arranged at a greater angle to the wheel circumference than the preceding set, a series of nozzle and return members mounted to coöperate with said wheel, each of said members being provided with an injecting nozzle to coöperate with the first set of wheel buckets and with a number of sets of

curved return passages coöperating with the succeeding sets of wheel buckets, one or more sets of return passages being substantially flat and arranged at a greater angle than the wheel buckets from which they receive fluid.

8. In axial flow elastic fluid turbines, a turbine wheel provided with a number of annular sets of lapping curved buckets, said wheel buckets being substantially flat and a succeeding set of said wheel buckets being arranged at a greater angle to the wheel circumference than the preceding set, a series of nozzle and return members mounted to coöperate with said wheel, each of said members being provided with an injecting nozzle to coöperate with the first set of wheel buckets and with a number of sets of curved return passages coöperating with the succeeding sets of wheel buckets.

9. In axial flow elastic fluid turbines, a turbine wheel provided with a number of annular sets of lapping curved buckets, said wheel buckets being substantially flat and a number of the succeeding sets of said wheel buckets being arranged at a greater angle to the wheel circumference than the preceding set and a number of the succeeding sets of said wheel buckets having a greater axial width than the preceding set, a series of return members mounted to coöperate with said wheel, each of said members being provided with an injecting nozzle to coöperate with the first set of wheel buckets and with a number of sets of curved return passages coöperating with the succeeding sets of wheel buckets, one or more sets of return passages being arranged to deliver fluid at a greater angle than the wheel buckets from which they receive fluid.

10. In axial flow elastic fluid turbines, a turbine wheel provided with a number of annular sets of lapping curved buckets, said wheel buckets being substantially flat and a number of the succeeding sets of said wheel buckets being arranged at a greater angle to the wheel circumference than the preceding set, a series of return members mounted to coöperate with said wheel, each of said members being provided with an injecting nozzle to coöperate with the first set of wheel buckets and with a set of curved return passages coöperating with the succeeding set of wheel buckets, one or more sets of return passages being arranged to deliver fluid at a greater angle than the wheel buckets from which they receive fluid.

11. In axial flow elastic fluid turbines, a turbine wheel provided with a number of annular sets of lapping curved buckets, said wheel buckets being substantially flat and a number of the succeeding sets of said wheel buckets being arranged at a greater angle to the wheel circumference than the preceding set.

12. In axial flow elastic fluid turbines, a turbine wheel provided with a number of annular sets of lapping curved buckets, said wheel buckets being substantially flat and a succeeding set of said wheel buckets being arranged at a greater angle to the wheel circumference than the preceding set.

13. In axial flow elastic fluid turbines, a turbine wheel provided with a number of annular sets of lapping curved buckets, a succeeding set of said wheel buckets being arranged at a greater angle to the wheel circumference than the preceding set.

14. In axial flow elastic fluid turbines, a turbine wheel provided with a number of annular sets of lapping curved buckets, a succeeding set of said wheel buckets being arranged at a greater angle to the wheel circumference than the preceding set and a succeeding set of said wheel buckets having a greater axial width than the preceding set.

15. In axial flow elastic fluid turbines, a turbine wheel provided with a number of annular sets of lapping curved buckets, there being annular curved recesses in the edges of the partitions separating the different sets of buckets, a return member mounted to coöperate with said wheel, and provided with a number of sets of curved return passages coöperating with the sets of wheel buckets, there being annular curved recesses formed in the edges of the partitions between the different sets of return passages.

16. In axial flow elastic fluid turbines, a turbine wheel provided with a number of annular sets of lapping curved buckets, a succeeding set of said wheel buckets being arranged at a greater angle to the wheel circumference than a preceding set, there being annular curved recesses in the edges of the partitions separating the different sets of buckets, a return member mounted to coöperate with said wheel, and provided with a number of sets of curved return passages coöperating with the sets of wheel buckets, there being annular curved recesses formed in the edges of the partitions between the different sets of return passages.

17. In axial flow elastic fluid turbines, a turbine wheel provided with a number of annular sets of lapping curved buckets, a succeeding set of said wheel buckets being arranged at a greater angle to the wheel circumference than a preceding set, there being annular curved recesses in the edges of the partitions separating the different sets of buckets, a return member mounted to coöperate with said wheel, and provided with a number of sets of curved return passages coöperating with the sets of wheel buckets.

18. In axial flow elastic fluid turbines, a turbine wheel provided with a number of annular sets of lapping curved buckets, a

succeeding set of said wheel buckets being arranged at a greater angle to the wheel circumference than a preceding set, a return member mounted to coöperate with 5 said wheel, and provided with a number of sets of curved return passages coöperating with the sets of wheel buckets, there being annular curved recesses formed in the edges of the partitions between the different sets 10 of return passages.

19. In axial flow elastic fluid turbines, a cast turbine wheel provided with a number of annular sets of lapping curved buckets, there being annular curved recesses in the 15 edges of the partitions separating the different sets of buckets, a series of cast integral nozzle and return members mounted to coöperate with said wheel, each of said members being provided with a plurality of injecting nozzles to coöperate with the first set 20 of wheel buckets and with a number of sets of curved return passages coöperating with the succeeding sets of wheel buckets and advancing substantially diagonally across said 25 wheel, there being annular curved recesses formed in the edges of the partitions between the different sets of return passages and there being relief spaces between adjacent members to allow premature escape of 30 retarded motive fluid from said wheel buckets.

20. In axial flow elastic fluid turbines, a turbine wheel provided with a number of annular sets of lapping curved buckets, there 35 being annular curved recesses in the edges of the partitions separating the different sets of buckets, a series of nozzle and return members mounted to coöperate with said wheel, each of said members being provided 40 with an injecting nozzle to coöperate with the first set of wheel buckets and with a number of sets of curved return passages coöperating with the succeeding sets of wheel buckets and advancing substantially 45 diagonally across said wheel, there being annular curved recesses formed in the edges of the partitions between the different sets of return passages and there being relief spaces between adjacent members to allow 50 premature escape of retarded motive fluid from said wheel buckets.

21. In axial flow elastic fluid turbines, a turbine wheel provided with a number of annular sets of lapping curved buckets, a 55 series of nozzle and return members mounted to coöperate with said wheel, each of said members being provided with an injecting nozzle to coöperate with the first set of wheel buckets and with a number of sets of 60 curved return passages coöperating with the succeeding sets of wheel buckets and advancing substantially diagonally across said wheel, and there being relief spaces between adjacent members to allow premature escape

of retarded motive fluid from said wheel 65 buckets.

22. In axial flow elastic fluid turbines, a turbine wheel provided with a number of annular sets of lapping curved buckets, a series of nozzle and return members mounted 70 to coöperate with said wheel, each of said members being provided with an injecting nozzle to coöperate with the first set of wheel buckets and with a set of curved return passages coöperating with the succeeding 75 set of wheel buckets and there being relief spaces between adjacent members to allow premature escape of retarded motive fluid from said wheel buckets.

23. In axial flow elastic fluid turbines, a 80 turbine wheel provided with a number of annular sets of curved buckets, a series of return members mounted to coöperate with said wheel, each of said members being provided with a number of sets of curved 85 return passages coöperating with the succeeding sets of wheel buckets and advancing substantially diagonally across said wheel, there being relief spaces between adjacent members to allow premature escape of retarded 90 motive fluid from said wheel buckets.

24. In axial flow elastic fluid turbines, a turbine wheel provided with a number of annular sets of curved buckets, a series of return members mounted to coöperate with 95 said wheel, each of said members being provided with a set of curved return passages coöperating with the succeeding set of wheel buckets, there being relief spaces between adjacent members to allow premature escape 100 of retarded motive fluid from said wheel buckets.

25. In axial flow elastic fluid turbines, a cast turbine wheel provided with a number of annular sets of lapping curved buckets, a 105 series of nozzle and return members mounted to coöperate with said wheel, each of said members being provided with one or more injecting nozzles to coöperate with the first set of wheel buckets and with a number of 110 sets of curved return passages coöperating with the succeeding sets of wheel buckets and advancing substantially diagonally across said wheel, there being trailing return passages formed in said return members arranged behind the nozzle coöperating 115 with such members and there being relief spaces between adjacent members to allow premature escape of returned steam from said wheel buckets.

26. In axial flow elastic fluid turbines, a cast turbine wheel provided with a number of annular sets of lapping curved buckets, a series of nozzle and return members mounted to coöperate with said wheel, each of said 125 members being provided with one or more injecting nozzles to coöperate with the first set of wheel buckets and with a number of

sets of curved return passages coöperating with the succeeding sets of wheel buckets, there being trailing return passages formed in said return members arranged behind the 5 nozzle coöperating with such members, and there being relief spaces between adjacent members to allow premature escape of returned steam from said wheel buckets.

27. In axial flow elastic fluid turbines, a 10 cast turbine wheel provided with a number of annular sets of lapping curved buckets, a series of separate nozzle and return members mounted to coöperate with said wheel, each of said members being provided with one or 15 more injecting nozzles to coöperate with the first set of wheel buckets and with a set of curved return passages coöperating with the succeeding set of wheel buckets, there being trailing return passages formed in said return 20 members arranged behind the nozzle coöperating with such members.

28. In axial flow elastic fluid turbines, a cast turbine wheel provided with a number of annular sets of lapping curved buckets 25 having flattened curved bottoms, a plurality of injecting nozzles to coöperate with one set of buckets and return members provided with a number of sets of curved return passages coöperating with succeeding sets of 30 wheel buckets, said wheel buckets being substantially flat and a number of the succeeding sets of said wheel buckets being arranged at a greater angle to the wheel circumference than the preceding set and a 35 number of the succeeding sets of said wheel buckets having a greater axial width than the preceding set, one or more sets of return passages being substantially flat and arranged at a greater angle than the wheel 40 buckets from which they receive motive fluid and one of said sets of return passages being warped and arranged to return the fluid to the wheel buckets at a less angle to the wheel circumference than said fluid was received to pass the motive 45 fluid a number of times through said wheel buckets at progressively increasing angles and to reduce the angle of returning fluid before again passing it through the wheel buckets at progressively increasing angles. 50

29. In axial flow elastic fluid turbines, a turbine wheel provided with a number of annular sets of lapping curved buckets, a plurality of injecting nozzles to coöperate 55 with one set of buckets and return members provided with a number of sets of curved return passages coöperating with succeeding sets of wheel buckets, said wheel buckets being substantially flat and a number of the 60 succeeding sets of said wheel buckets being arranged at a greater angle to the wheel circumference than the preceding set, one or more sets of return passages being substantially flat and arranged at a greater angle

than the wheel buckets from which they receive motive fluid and one of said sets of return passages being warped and arranged to return the fluid to the wheel buckets at a less angle to the wheel circumference than said fluid was received to pass the motive fluid 65 a number of times through said wheel buckets at progressively increasing angles and to reduce the angle of returning fluid before again passing it through the wheel buckets at progressively increasing angles. 70

30. In axial flow elastic fluid turbines, a turbine wheel provided with a number of annular sets of lapping curved buckets, a plurality of injecting nozzles to coöperate with one set of buckets and return members 80 provided with a number of sets of curved return passages coöperating with succeeding sets of wheel buckets, a number of the succeeding sets of said wheel buckets being arranged at a greater angle to the wheel circumference than the preceding set, one or 85 more sets of return passages being substantially flat and arranged at a greater angle than the wheel buckets from which they receive motive fluid and one of said sets of return passages being warped and arranged to return the fluid to the wheel buckets at a less angle to the wheel circumference than said fluid was received to pass the motive fluid a number of times through said wheel 90 buckets at progressively increasing angles and to reduce the angle of returning fluid before again passing it through the wheel buckets at progressively increasing angles. 95

31. In axial flow elastic fluid turbines, a 100 turbine wheel provided with a number of annular sets of lapping curved buckets and a series of cast nozzle and return members mounted to coöperate with said wheel each of said members being provided with a plurality of injecting nozzles to coöperate with one set of said wheel buckets and with a 105 number of sets of curved return passages coöperating with succeeding sets of wheel buckets, one or more of said sets of return passages being substantially flat and arranged at a greater angle to the adjacent wheel circumference than the preceding set to progressively increase the angle at which the motive fluid is injected into the different 110 sets of wheel buckets.

32. In axial flow elastic fluid turbines, a turbine wheel provided with a number of annular sets of lapping curved buckets and a series of return members mounted to coöperate with said wheel each of said members being provided with a number of sets of curved return passages coöperating with succeeding sets of wheel buckets, one or more of said sets of return passages being 120 substantially flat and arranged at a greater angle to the adjacent wheel circumference than the preceding set to progressively increase the angle at which the motive fluid is injected into the different 125 sets of wheel buckets.

crease the angle at which the motive fluid is injected into the different sets of wheel buckets.

33. In axial flow elastic fluid turbines, a turbine wheel provided with a number of annular sets of lapping curved buckets and a series of return members mounted to co-operate with said wheel each of said members being provided with a number of sets of curved return passages coöperating with succeeding sets of wheel buckets, one or more of said sets of return passages being arranged at a greater angle to the adjacent wheel circumference than the preceding set to increase the angle at which the motive fluid is injected into the different sets of wheel buckets.

34. In axial flow elastic fluid turbines, a turbine wheel provided with a number of annular sets of lapping curved buckets and a series of return members mounted to co-operate with said wheel each of said members being provided with a number of sets of curved return passages coöperating with succeeding sets of wheel buckets, one or more of said sets of return passages being arranged at a greater angle to the adjacent wheel circumference than the preceding set to increase the angle at which the motive fluid is injected into the succeeding set of wheel buckets.

35. In axial flow elastic fluid turbines, a cast turbine wheel provided with a number of annular series of lapping curved buckets having flattened curved bottoms and coöperating injecting nozzles and return passages, a number of sets of said buckets making a greater angle to the wheel circumference than the preceding set and one or more of said sets of wheel buckets having a greater axial width than the preceding set.

36. In axial flow elastic fluid turbines, a turbine wheel provided with a number of annular series of lapping curved buckets, a set of said buckets making a greater angle to the wheel circumference than the preceding set and one or more of said sets of wheel buckets having a greater axial width than the preceding set.

37. In axial flow elastic fluid turbines, a turbine wheel provided with a number of annular series of lapping curved buckets, a set of said buckets making a greater angle to the wheel circumference than the preceding set.

38. In axial flow elastic fluid turbines, a turbine wheel provided with a number of annular sets of lapping curved buckets, a number of sets of said buckets being arranged at a greater angle to the wheel circumference than a preceding set and a series of return members mounted to coöperate with said wheel and advancing substantially diagonally across said wheel, each of said return members being provided with a

number of sets of curved return passages co-operating with the sets of wheel buckets, one or more sets of said return passages having greater axial width and being substantially flat and arranged at a greater angle to the wheel circumference than the preceding set. 70

39. In axial flow elastic fluid turbines, a turbine wheel provided with a number of annular sets of lapping curved buckets and a series of return members mounted to co-operate with said wheel each of said return members being provided with a number of sets of curved return passages coöperating with the sets of wheel buckets, one or more sets of said return passages having greater axial width and being arranged at a greater angle to the wheel circumference than the preceding set. 80

40. In axial flow elastic fluid turbines, a turbine wheel provided with a number of annular sets of lapping curved buckets and a series of return members mounted to co-operate with said wheel each of said return members being provided with a number of sets of curved return passages coöperating with the sets of wheel buckets, one or more sets of said return passages being arranged at a greater angle to the wheel circumference than the preceding set. 85

41. In elastic fluid turbines, a cast wheel rim formed of bronze having high co-efficient of expansion and provided with integrally cast bucket partitions and buckets, a plurality of sets of substantially radial bronze expansion spokes having high co-efficient of expansion secured to said rim, said spokes having ends formed with projections to be inclosed and gripped by inwardly projecting lugs cast on said rim, a wheel hub secured to the inner ends of said expansion spokes, the inner ends of said spokes being provided with projections and said hub being formed of cast ferrous metal of less co-efficient of expansion embracing and gripping said spoke ends and forming integral spoke supports loosely surrounding said spokes and allowing their radial expansion, spoke sleeves cast in said spoke supports and guiding said spokes in their radial expansion and side plates secured to said rim to inclose said spokes. 100

42. In elastic fluid turbines, a cast wheel rim formed of bronze having high co-efficient of expansion and provided with integrally cast bucket partitions and buckets, substantially radial bronze expansion spokes having high co-efficient of expansion secured to said rim, said spokes having ends formed with projections to be inclosed and gripped by inwardly projecting lugs cast on said rim, a wheel hub secured to the inner ends of said expansion spokes, the inner ends of said spokes being provided with projections and said hub being formed of cast ferrous metal of less co-efficient of expansion em- 110

bracing and gripping said spoke ends and forming integral spoke supports loosely surrounding said spokes and allowing their radial expansion, spoke sleeves cast in said spoke supports and guiding said spokes in their radial expansion.

43. In elastic fluid turbines, a cast wheel rim having high co-efficient of expansion and provided with integrally cast bucket partitions and buckets, substantially radial expansion spokes having high co-efficient of expansion secured to said rim, said spokes having ends formed with projections to be inclosed and gripped by inwardly projecting lugs cast on said rim, a wheel hub secured to the inner ends of said expansion spokes, the inner ends of said spokes being provided with projections and said hub being formed of cast metal of less co-efficient of expansion embracing and gripping said spoke ends and forming integral spoke supports loosely surrounding said spokes and allowing their radial expansion.

44. In elastic fluid turbines, a cast wheel rim having high co-efficient of expansion and provided with integrally cast bucket partitions and buckets, substantially radial expansion spokes having high co-efficient of expansion secured to said rim, said spokes having ends inclosed and gripped by said rim and a wheel hub secured to the inner ends of said expansion spokes, said hub being formed of metal of less co-efficient of expansion and having spoke supports loosely surrounding said spokes and allowing their radial expansion.

45. In elastic fluid turbines, a cast wheel rim having high co-efficient of expansion and provided with integrally cast bucket partitions and buckets, substantially radial expansion spokes having high co-efficient of expansion secured to said rim, and a wheel hub secured to the inner ends of said expansion spokes, said hub being formed of metal of less co-efficient of expansion and having spoke supports partly surrounding said spokes and allowing their radial expansion.

46. In elastic fluid turbines, a cast wheel rim having high co-efficient of expansion and provided with integrally cast bucket partitions and buckets, expansion spokes having high co-efficient of expansion secured to said rim, and a wheel hub secured to the inner ends of said expansion spokes, said hub being formed of metal of less co-efficient of expansion.

47. In elastic fluid turbines, a wheel rim having high co-efficient of expansion and provided with bucket partitions and buckets, substantially radial bronze expansion spokes having high co-efficient of expansion secured to said rim, a wheel hub secured to the inner ends of said expansion spokes, the inner ends of said spokes being provided with projections and said hub being formed

of cast ferrous metal of less co-efficient of expansion embracing and gripping said inner spoke ends and forming integral spoke supports loosely surrounding said spokes and allowing their radial expansion and spoke sleeves cast in said spoke supports and guiding said spokes in their radial expansion.

48. In elastic fluid turbines, a wheel rim having high co-efficient of expansion and provided with bucket partitions and buckets, substantially radial expansion spokes having high co-efficient of expansion secured to said rim, a wheel hub secured to the inner ends of said expansion spokes, said hub being formed of cast metal of less co-efficient of expansion embracing and gripping said inner spoke ends and forming integral spoke supports loosely surrounding said spokes and allowing their radial expansion, and spoke sleeves cast in said spoke supports and guiding said spokes in their radial expansion.

49. In elastic fluid turbines, a wheel rim having high co-efficient of expansion and provided with bucket partitions and buckets, substantially radial expansion spokes having high co-efficient of expansion secured to said rim, a wheel hub secured to the inner ends of said expansion spokes, said hub being formed of cast metal of less co-efficient of expansion forming integral spoke supports loosely surrounding the inner portions of said spokes and allowing their radial expansion, and spoke sleeves cast in said spoke supports and guiding said spokes in their radial expansion.

50. In elastic fluid turbines, a turbine wheel comprising substantially radial spokes of cuprous metal, a cast wheel rim having substantially the same co-efficient of expansion as said spokes and provided with bucket partitions and buckets and cast around the outer ends of said spokes and a wheel hub of ferrous metal cast around the inner ends of said spokes to effect close engagement and union therewith and allow the original casting strains in said rim to become relieved by cooling the same before connecting said hub thereto.

51. In elastic fluid turbines, a turbine wheel comprising spokes of wrought cuprous metal, a cast wheel rim provided with bucket partitions and buckets and cast around the outer ends of said spokes and a wheel hub cast around the inner ends of said spokes to effect close engagement and union therewith and allow the original casting strains in said rim to become relieved by cooling the same before connecting said hub thereto.

52. In elastic fluid turbines, a turbine wheel comprising substantially radial spokes of wrought bronze metal, a cast wheel rim having substantially the same coefficient of expansion as said spokes and provided with

bucket partitions and buckets and cast around the outer ends of said spokes and a wheel hub of ferrous metal cast around the inner ends of said spokes to effect close engagement and union therewith and allow the original casting strains in said rim to become relieved by cooling the same before connecting said hub thereto.

53. In elastic fluid turbines, a turbine wheel comprising spokes of wrought metal, a cast wheel rim provided with bucket partitions and buckets and cast around the outer ends of said spokes and a wheel hub cast around the inner ends of said spokes 15 to allow the original casting strains in said rim to become relieved by cooling the same before connecting said hub thereto.

54. In elastic fluid turbines, a turbine wheel comprising spokes, a cast wheel rim substantially the same coefficient of expansion as said spokes and provided with bucket partitions and buckets and cast around the outer ends of said spokes and a wheel hub attached to said spokes to allow the original 25 casting strains on said rim to become relieved by cooling before connecting said hub thereto.

55. In elastic fluid turbines, a turbine wheel comprising spokes, a cast wheel rim provided with bucket partitions and turbine buckets and cast around portions of said spokes, and a wheel hub secured to the inner ends of said spokes to allow the original casting strains on said rim to become relieved by cooling the same before connecting said hub thereto.

56. In elastic fluid turbines, a cast wheel

rim having high coefficient of expansion and provided with integral bucket partitions and turbine buckets, expansion spokes having high coefficient of expansion extending inward from said rim, a wheel hub cast around the inner ends of said expansion spokes, said hub being formed of cast metal of less coefficient of expansion.

40
45

57. In axial flow elastic fluid turbines, a turbine wheel provided with a number of annular sets of lapping curved buckets, a series of nozzle and return members mounted to coöperate with said wheel, each of said members being provided with an injecting nozzle to coöperate with the first set of wheel buckets and with a number of sets of curved return passages coöperating with the succeeding sets of wheel buckets 55 and advancing substantially diagonally across said wheel.

50

58. In axial flow elastic fluid turbines, a turbine wheel provided with a number of annular sets of lapping curved buckets and 60 a series of return members mounted to coöperate with said wheel and advancing substantially diagonally across said wheel each of said return members being provided with a number of sets of curved return passages 65 coöperating with the sets of wheel buckets, one or more sets of said return passages being arranged at a greater angle to the wheel circumference than the preceding set.
